**COKE QUENCHING METHOD AND APPARATUS
WITH COOL COKE RECYCLE**
Vaughn Mansfield, 5340 Delmar Blvd., St. Louis, Mo.
Filed Nov. 2, 1959, Ser. No. 850,389
11 Claims. (Cl. 202—37)

This invention relates to a combined coke cooler and air preheater for a coking stoker. More particularly, the invention concerns a method and apparatus wherein a portion of cooled coke is recycled into a stream of hot coke to reduce the temperature of the stream below its ignition temperature, whereby air may be circulated through the coke stream so as to preheat the air while cooling the coke.

The invention is particularly adapted for use with coking stokers of the type shown in the copending applications of Mansfield, entitled Method and Apparatus for Continuous Coke Production While Extracting Low Temperature Volatiles, Serial No. 820,213, filed June 15, 1959, and Method and Apparatus for Producing Coke and Heat While Extracting Low Temperature Volatiles, Serial No. 850,388, filed November 2, 1959. In order to appreciate the function of the invention, it is sufficient to understand that, in coking stokers of the type above referred to, the coal is fed onto a travelling grate stoker to form a bed which passes slowly through an oven. Preheated fuel gas is fed upwardly through the bed so as to raise the bed temperature sufficiently to drive off most of the volatile matter from the coal, and limited oxidation in the bed occurs. As the nearly completely carbonized hot coal bed passes off the output end of the stoker, sufficient residual volatiles remain in the coke so that, if air were then used to cool it, the fixed carbon would ignite, and if water were used to quench it, water gas would be created and excessive amounts of coke would be consumed.

According to this invention, the nearly devolatilized hot coke discharged from the output end of the coking oven is first caught and maintained in a column retort, or devolatilizing cooker. As the coke column progresses slowly downwardly in the cooker, the latent heat of the coke drives off virtually all of the residual volatiles, which pass back into the coking oven. While part of the latent heat in the coke is given up as the coke progresses downwardly through the cooker, the temperature of the coke discharged from the cooker is sufficiently high that, if it were exposed to air, it would instantly ignite and burn to ash. The primary object of the method and apparatus of this invention is to blend in, with the hot coke discharged from the cooker, sufficient cool coke so as to reduce the temperature of the aggregate blend below its ignition temperature. It is intended that air be then circulated through the partly cooled non-ignitable coke so as to cool it further, and to pre-heat the air, the preheated air then being utilized in the coking oven.

These and other objects will be apparent in the following specification and drawing, in which the sole figure shows the parts in diagrammatic cross-section.

Referring now to the drawing, in which like reference numerals denote similar elements, from the output end 12, of a coking oven, hot coke 4 falls from the end of a travelling grate stoker 5 through a discharge opening 6. For purposes of understanding the subject invention, it is sufficient to note that the coke 4 has been nearly completely carbonized in an atmosphere with sufficiently small amounts of oxygen to support only limited combustion within the bed, and that the coke, as it falls through the discharge opening 6, is between 1,650° F. and 1,800° F. Although the coke is nearly completely carbonized, nevertheless there remains a small residue of volatile matter which, if exposed to temperature in the

2

range of 1,650° F. to 1,800° F. for a sufficient length of time, will be driven off.

The hot coke falling through discharge opening 6 is caught and maintained in a column, as indicated at 8, in a devolatilizing cooker 10 having refractory walls 12. The column 8 of hot coke is permitted to move slowly downwardly in cooker 10 and it remains in the column sufficiently long for the latent heat in the coke to drive off virtually all of the residual volatiles which rise, as indicated by the arrow 14, and drift back into a coking oven, in which they are consumed. As the stack of hot coke moves slowly downwardly in cooker 12, heat is lost so that, by reaching the outlet 16 of the cooker, the temperature of the coke will be assumed to be about 1,650° F. Virtually no air is permitted to flow upwardly through coke column 8, the coke being discharged from cooker 10 by a cast iron drum feeder 18, or a cast iron screw feeder, which passes the coke outwardly beneath the gate 20. It will be understood that the coke emerging from outlet 16, while somewhat cooler than it was upon leaving the coking oven, is nevertheless sufficiently hot so that it would immediately burn if air were supplied to it for cooling.

The hot coke discharged from cooker 10 by drum feeder 18 is caught and maintained in a downwardly moving mass in a retort 22. From retort 22 the coke is discharged through an outlet 24 onto a downwardly inclined vibrating cooler deck 26, on which the coke is spread to form a layer by a conventional spreader 27.

Vibrating cooler deck 26 has a solid upper section 28 and a lower perforate screen section 30, both sections being provided with suitable supports diagrammatically indicated at 32 and a conventional vibrating mechanism 34. An enclosure 36 confines the region above the solid section 28 of the vibrating cooler deck. A vent 38 leads upwardly from enclosure 36 into the upper portion of retort 22 and a second vent 39 leads from the top of retort 22 back into the outlet end of coking oven 2. Air leaking into enclosure 36, in such small quantities that it will not result in significant burning of the hot coke, sweeps off dust from the coke evolved during the agitation of the coke as it moves along the solid deck section 28 and, previously, as it falls into retort 22. The dust returned to the coking oven via vents 38 and 39 is consumed in the coking oven. As the coke passes along the solid section of the shaking conveyor, it is first spread to form a thin layer, and the thorough and intimate intermingling of the hot and cool coke, started when the two were blended in the retort, is completed so that no excessively hot spots or incandescence exist in the blend as it passes onto the screen section of the shaking conveyor.

A hood 40 is disposed over the screen section 30 of vibrator cooling deck 26 and an air conduit 42 leads from below screen section 30. Floating air seals 44a and 44b are provided beneath the lower edges of hood 40 at the upper and lower ends of the screen section 30. Ordinarily, and but for the subject invention, the temperature of the coke bed, as it passes onto screen section 30 of the vibrating cooler deck, would still be well above the ignition point so that it would burn if attempt were made to cool it by air circulating through screen section 30. The coke bed, however, is cooled and ignition is prevented as follows.

As the coke drops off the lower end of the screen section 30 of vibrating cooler deck 26, it falls onto a gathering conveyor 45 which delivers it to a hopper 46. Part of the coke is discharged from hopper 46 to a loading conveyor as indicated by the arrow 48. However, another portion of the coke from hopper 46 is recycled according to the demands of a temperature sensing device 50 in re-

retort 22. The device 50 senses the temperatures of the coke mass near the bottom of retort 22 and, by means of a connection indicated by the broken line 52, provides a signal which controls a mechanical actuating unit 54 which, in turn, moves an apportioner 56 in hopper 46. Apportioner 56 splits the stream of cool coke falling through hopper 46 into two portions which vary in relative amounts, depending on the demands of temperature sensing device 50. Part of the cool coke from hopper 46 is returned via an outlet 58 in hopper 46, a recycle conveyor diagrammatically indicated at 60 and a recycle input 62 into the top of retort 22, from which it drops and mingles with the mass of hot coke discharged into the retort by drum feeder 18 from cooker 10. If the temperature sensed by device 50, which may be a thermocouple or other conventional temperature sensing unit, is higher than a predetermined degree, i.e., 600° F., mechanical actuating unit 54 is thereby controlled so as to swing apportioner 56 so as to increase the amount of coke recycled via conveyor 60 back into retort 22. If the temperature sensed by device 50 is below the given degree, apportioner 56 will be actuated by unit 54 so as to decrease the amount of cool coke recycled by conveyor 60, and increase the amount discharged on to the loading conveyor. The desired temperature of the coke, as sensed by device 50, emerging from retort outlet 24 onto vibrating cooler deck 26 should be such that the coke bed emerging from the lower end of enclosure 36 is below the point at which the coke will ignite when the air flows through it. The highest permissible temperature of the coke bed, as the latter leaves the solid section 28 of the vibrator cooler deck, is estimated to be 600° F. Cool air from a supply 64 is fed downwardly through hood 40, as indicated by arrows 66, and downwardly through the coke bed on screen section 30, through the screen section, and exhausted via conduit 42 as indicated by arrows 68. The air, having extracted heat from the coke bed, is preheated and used for various purposes in the coking oven. By the time the coke on screen section 30 reaches floating air seal 44b, it will have been cooled to a temperature of approximately 200° F. For starting the process, a supply of cool coke should be retained for recycling, or the coke in retort 22 can be water or steam quenched, on a temporary basis, until a starting supply of cool coke is obtained.

If desired, in order to prevent plugging of screen deck 30 and to handle the siftings through the screen deck, the direction of air flow may be reversed in the direction of broken arrows 66', 68' so that air is pulled upwardly through the screen deck. In that event, a solid deck 30a, diagrammatically shown in broken lines, would be spaced below the screen deck so as to catch the siftings, and cooling air would be drawn in from the ends from vents 70a and 70b, and also through side vents, not shown. This mode of air cooling would also have certain advantages in reducing the amount of dust escaping through air seal 44b.

The temperatures estimated for the various steps in the process may vary according to the temperature of the coke upon leaving the stoker, the amount of heat lost in the cooker, the ignition temperature of the coke, and the temperature and amount of coke recycled into the retort. In interpreting the claims, it will be understood that the starting temperature of the coke, in entering the quenching apparatus, is substantially above the degree at which it would ignite if exposed to substantial amounts of air; the coke, as it starts along the screen section of the shaking conveyor, is below the temperature at which it will ignite when sufficient air is blown through to cool it; and, upon leaving the hopper at the end of the process, the coke is not only sufficiently cool that it may be handled but, also, that the recycled cool coke will cool the hot coke to below its ignition temperature. It will be understood also that the volume and size of the cooker, retort and shaking conveyor, and rates of flow through the

cooker, retort and along the shaking conveyor are sufficiently large to handle the output of the coking oven and (for the retort and shaking conveyor) the output of the coking oven plus the recycled cool coke. The rate of flow through the shaking conveyor may be changed by altering the tilt of the conveyor or by changing the shaking rate.

According to present estimates, it will be necessary to recycle about 35,437 lbs. of cool coke, at 200° F. per 10 each 13,500 lbs. of hot coke falling into retort 22 so that the temperature of the resultant blend leaving the retort will be about 600° F.

The invention is not limited to the details of the apparatus and the method disclosed and described hereinbefore, but is intended to cover all substitutions, modifications and equivalents within the scope of the following claims.

I claim:

- 20 1. The method of quenching hot coke from a temperature substantially above an ignition point at which the coke would readily burn if exposed to air in substantial quantities, to an end-of-process temperature greatly below the point at which the coke would ignite if exposed to air in quantities sufficient to cool it, said method comprising; confining the hot coke in a non-oxidizing atmosphere, reducing the temperature of the confined coke to slightly below the ignition point by the steps including blending cool coke with the hot coke and intermingling the hot coke with the cool in said non-oxidizing atmosphere so as to transfer heat from the hot coke to the cool coke until the temperature of the resultant blend is below the ignition point thereof in air, and subsequently air-cooling the blended coke to said end-of-process temperature.
- 25 35 2. The method of quenching hot coke from a temperature substantially above an ignition point at which the coke would readily burn if exposed to air in substantial quantities, to an end-of-process temperature greatly below the ignition point, said method comprising; confining the hot coke in a non-oxidizing atmosphere, reducing the temperature of the confined coke to slightly below the ignition point by the steps including recycling cool coke and blending the same with the hot coke and intermingling the hot coke with the cool in said non-oxidizing atmosphere so as to transfer heat from the hot coke to the cool coke until the temperature of the resultant blend is below the ignition point thereof in air, and subsequently air-cooling the blended coke to said end-of-process temperature.
- 40 45 50 3. Apparatus for quenching hot coke, comprising a substantially air-tight receiver having an input and an output for receiving and confining the hot coke in a substantially oxygen-free atmosphere; conveyor means having an input for receiving coke from the receiver output and for transporting the same from the receiver, means for spreading the coke on the conveyor to form a relatively thin layer thereon, means for passing cool air through the layer of coke in transit on the conveyor, and means for recycling a portion of the air-cooled coke from the conveyor back to the receiver, whereby to transfer heat from the hot coke in the receiver to the recycled cool coke.
- 55 60 65 70 75 4. Apparatus for quenching hot coke comprising cooker means for receiving hot coke and maintaining the same in a mass slowly moving therethrough, substantially air-tight receiver means for receiving and holding the coke from said cooker, said receiver having means for discharging coke therefrom, a shaking conveyor having an input portion comprising an imperforate, substantially air-tight deck section for receiving coke from said discharge means, means forming a substantially air-tight hood over the imperforate deck section, and an output portion comprising a perforate deck section for receiving coke from said imperforate section, means for circulating a cooling medium through the coke on said second sec-

tion whereby to cool the coke thereon, and means for recycling a portion of the fluid-cooled coke from said second section back into said receiver.

5. Apparatus for quenching hot coke comprising cooker means for receiving hot coke and maintaining the same in a mass slowly moving therethrough, substantially air-tight receiver means for receiving and holding the coke from said cooker, said receiver having means for discharging coke therefrom, a shaking conveyor having an input portion comprising an imperforate, substantially air-tight deck section for receiving coke from said discharge means, means forming a substantially air-tight hood over the imperforate deck section, and an output portion comprising a perforate deck section for receiving coke from said imperforate section, means for circulating a cooling medium through the coke on said perforate section whereby to cool the coke thereon, means for recycling a portion of the fluid-cooled coke from said second section back into said receiver to form a blend with the coke received from the cooker, means in the receiver adjacent the discharge means thereof for sensing the temperature of the blend prior to the reception thereof on the second section of the conveyor, and means for controlling the amount of recycle coke in accordance with the sensed temperature of the blend.

6. Apparatus for quenching hot coke, comprising a substantially air-tight retort for receiving hot coke, said retort having a coke outlet, a downwardly inclined shaking conveyor having a solid upper deck section for receiving coke on its upper side from the retort outlet and a perforate lower deck section, means confining the upper side of said solid deck section in a substantially air-free atmosphere, means for circulating cooling air through the perforate lower deck section and the coke thereon, and means for recycling a portion of the cooled coke from said perforate deck section back into said retort.

7. Apparatus for quenching hot coke, comprising a substantially air-tight retort for receiving hot coke, said retort having a coke outlet, a downwardly inclined shaking conveyor having a solid upper deck section for receiving coke on its upper side from the retort outlet and a perforate lower deck section, means confining the upper side of said solid deck section in a substantially air-free atmosphere, means for circulating cooling air through the perforate lower deck section and the coke thereon, means for recycling a portion of the cooled coke back into said retort and for blending the same with the hot coke therein, temperature sensing means in said retort adjacent the coke outlet, and means for controlling the amount of recycled coke in accordance with the sensed temperature of the blend.

8. Apparatus for quenching hot coke, comprising a cooker receptacle for maintaining the hot coke in a ver-

tical column, said cooker receptacle having an input at its upper end and a substantially air-tight dispenser at its lower end, a substantially air-tight retort for receiving coke from said dispenser, said retort having a coke outlet, a downwardly inclined shaking conveyor having a solid upper deck section for receiving coke on its upper side from the retort outlet and a perforate lower deck section, means confining the upper side of said solid deck section in a substantially air-free atmosphere, means for

5 10 15 20 25 30 35 40

circulating cooling air through the perforate lower deck section and the coke thereon, means for receiving the cooled coke from said perforate deck section, and means for recycling a portion of the cooled coke back into said retort.

9. Apparatus for quenching hot coke derived from a coking oven comprising a cooker receptacle for receiving and maintaining the hot coke derived from said oven in a vertical column, said cooker receptacle having an input at its upper end communicating with the oven and a substantially air-tight dispenser at its lower end, a substantially air-tight retort for receiving coke from said dispenser, said retort having a coke outlet, a downwardly inclined shaking conveyor having a solid upper deck section for receiving coke on its upper side from the retort outlet and a perforated lower deck section, means confining the upper side of said solid deck section in a substantially air-free atmosphere, means for circulating cooling air through the perforate lower deck section and the coke thereon, means for receiving the cooled coke from said perforate deck portion, and means for recycling a portion of the cooled coke back into said retort whereby to blend the same with the hot coke from said dispenser.

10. The combination claimed in claim 9, means in said retort for sensing the temperature of the blend, and means for controlling the amount of coke recycled in accordance with the sensed temperature of the blend.

11. The combination claimed in claim 9, means for venting dust from said conveyor, and means for feeding the vented dust back into said oven.

45 50

12. The combination claimed in claim 9, means for venting dust from said conveyor, and means for feeding the vented dust back into said oven.
